CURTAIN ROD ELEVATOR

Stephen Hoffer, Flushing, N. Y.

Application March 12, 1953, Serial No. 341,995

2 Claims. (Cl. 248—265)

This invention relates to curtain rod elevators and particularly to that type which can be raised and lowered by a person standing on the floor.

The invention contemplates the provision of a simple and inexpensive two-piece support for each end of a curtain rod and the conventional bracket therefor, which support may be quickly and easily installed on a window frame by a person standing on the floor and easily manipulated to bring the curtain and its rod within reach without the necessity for climbing upon a chair or ladder.

The invention further contemplates the provision of combined guide and locking means integral with the fixed member of the elevator for engaging and adequately maintaining the lower end of the movable member of the elevator normally in the raised position thereof, with the upper end braced and secured to the upper end of a similar parallel cooperating elevator by the curtain rod itself, whereby the curtain installation forms a braced structure without the need for special guides or braces at the top of the window frame, and the structure is properly guided in its upward and downward movements, as when it is desired to mount, remove or replace the curtain.

The invention further contemplates the provision of a one-piece accessible bracket capable of locking a one-piece upright curtain-holding slide in any one of a number of positions while permitting tilting of the slide in the lowered position thereof sufficiently to clear and to pass the window sill.

The invention further contemplates the provision of a two-piece curtain raising device adapted to be inexpensively stamped of suitable sheet material such as sheet metal and quickly assembled and installed, the relatively short member of the device being fixed to the window frame in accessible position and the other long member being slidable in and normally supported and locked at its lower end only by the short member, but being adapted to be supported and locked not only in the lowermost position thereof but also in an intermediate position by the short member.

The various objects of the invention will be clear from the description which follows and from the drawings, in which—

Fig. 1 is an elevational view of a typical window, showing my device applied thereto and showing in dash-dot lines, the movable support members and the curtain rod in the lowermost positions thereof.

Fig. 2 is a side elevational view of Fig. 1.

Fig. 3 is a foreshortened perspective view of the two-piece support, showing one form of the means for holding a double curtain rod bracket in place on the slide, and showing the position assumed by the slide during the vertical movement thereof.

Fig. 4 is a fragmentary vertical sectional view thereof, taken on the line 4—4 of Fig. 5.

Fig. 5 is a horizontal sectional view of the support taken on the line 5—5 of Fig. 4.

Fig. 6 is a fragmentary elevational view of the upper

flange of the support bracket showing in dash-dot lines how the flange may be bent to adjust the angle of tilting of the slide to insure that in the lowermost position thereof, the slide clears the window sill.

5 Fig. 7 is a perspective view of a modified form of the securing means for the curtain rod bracket.

Figs. 8 and 9 are top plan and side elevational views respectively of another modified form of the securing means.

10 In the practical embodiment of the invention shown by way of example, a pair of substantially identical supports for the curtain rod 10 are arranged to extend vertically along the upper parts of the respective sides of the window frame 11. Each of the supports consists of two

15 parts, one being a fixed relatively short U-shaped bracket 12 and the other an elongated channel-shaped slide 13, both being conveniently and inexpensively stamped of suitable sheet material. The bracket 12 is of approximately one eighth of the height of the slide and is of generally

20 U-shaped form, having an upper flange 14 and a dissimilar lower substantially horizontal flange 15, the flanges being integrally connected by the upright web 16.

The bracket is installed merely by securing the web 16 to a side of the window frame at approximately shoulder

25 height as by means of suitable screws or the like passing through the holes 17 of the web and into the frame (Fig. 2). Such installation may be performed by relatively unskilled persons standing on the floor and does not require the use of a ladder or chair. The hole 18 in the

30 upper flange 14 is of about the same width laterally as that of the hole 19 in the lower flange, the holes 18 and 19 being aligned laterally to guide the slide 13 in its movement and to prevent lateral tilting, shifting or rattling of the slide relatively to the bracket. However,

35 the corresponding end edges of said holes 18 and 19 are not aligned transversely, since transverse tilting of the slide as shown by the dash-dot lines of Figs. 2 and 4, is desirable as will be later more fully explained.

As viewed in Figs. 4 and 5, the left hand end edge

40 20 of the hole 18, which edge will be referred to as the "rear" edge, serves as a stop to limit the tilting action of the slide 13 and consequently is not directly above the corresponding left hand end or rear edge 21 of the lower hole 19. In other words, the hole 18 is extended horizontally rearwardly so that its rear edge 20 is not directly

45 or vertically above the corresponding edge 21, but is to the left of said edge 21. The right hand end or front edge 22 of the hole 18 is preferably directly above the innermost point 25 of the bent tongue 24 which projects from the front edge 27 of and into the lower hole 19.

50 Said tongue constitutes a combined guiding and locking means to lock the slide in a selected vertically adjusted position thereof. The tongue is integral with the material of the lower flange 15, being formed from the material removed to form the hole 19. A rearwardly convex

55 bend 23 is made at the base of the tongue for camming action against the slide in a manner to be later described. The tongue 24 is inclined upwardly and forwardly from the bend 23 toward the free end 26 thereof so that the horizontally projected distance between the tongue end

60 26 and the right hand or front edge 27 of the hole 19 is about the same as the thickness of the web 28 of the channel slide 13, whereby said web may pass in front of the tongue end 26 and be locked between the tongue and said edge 27 against forward and rearward movement

65 as shown in Figs. 4 and 5. The edge 27 is therefore to the right or in front of the edge 22 and not directly therebelow.

The slide 13 is of U-shaped cross section, being readily formed of suitable sheet material into the form of a channel wherein the web 28 joins the side flanges 29 thereof. A number of spaced apart perforations as 30

are made in the web for the passage of the tongue 24 into the interior of the slide when the slide is to be locked against all but upward movement. The slide is long enough to reach from a point below the bracket 12 to the top of the window frame. The top of the slide is therefore spaced substantially away from the top of the bracket and is also free of guides where the curtain rod is to be arranged. As has been indicated, the slide may readily be lowered in the bracket to position the curtain rod and the curtain carried thereby within easy reach of a person standing on the floor at the window.

In the locked position of Fig. 4, that part of the slide at and below the tongue 24 cannot move in any direction except upwardly, and the weights of the slide, curtain rod and curtain are supported at the base of the tongue. The upper ends of the pair of slides may, however, be tilted rearwardly as shown in Figs. 2 and 4 until the rearmost edges of the flanges 29 rest against and are stopped by the edge 20 of the upper hole 17. In this position, the upper ends of the slides may, if desired, rest against the window frame and hence resists rattling and displacement. It will be noted that the position of the rear edge 20 with respect to the front edges 22 and 27 of the holes in the bracket flanges, determines the amount of tilt of the slide and that the minimum amount of such tilt occurs when the tongue 24 rides on the front face of the web 28 as shown by the dash-dot lines of Fig. 4. To attain the locking and tilting action described, each perforation 30 is of greater height than that of the tongue to permit said tongue to pass freely therethrough and to the rear of the web on the forward movement of the adjacent part of the slide. When the slide is thereafter released, the weight thereof aided by the weight of the parts carried thereby, causes the slide to drop to the position of Fig. 4 wherein the wall or edge around the perforation 30 has passed in front of the tongue and rests on the base of the tongue in front of the bend 23. In the normal or operative positions of the slides, they have been moved upwardly through the holes 18 and 19 of the brackets to the uppermost positions thereof (Figs. 1 and 2). If the slide is pushed rearwardly while it is being raised, the bend 23 of the tongue does not enter any of the perforations 30. Instead, the front surface of the web 28 is guided by the front edge 22 of the upper hole 18 as well as by the rear surface of the bend 23 as shown by the dash-dot lines of Fig. 4. It may also, if desired, be guided by the rear edge 21 of the lower hole 19. If no rearward pressure is applied to the slide during the upward movement thereof and if there is any tendency for the tongue to enter a perforation 30, then the bend 23 of the tongue strikes the lower edge of the perforation and acts as a cam to move the slide rearwardly and to withdraw the tongue out of the perforation into which the tongue may have entered partly or completely.

The slide is preferably tilted into the position shown in Fig. 4 when completely raised and may also be tilted enough to clear the window sill 31 of the window 11 (Fig. 2) when it is disengaged from the tongue and lowered, tilting being permitted because of the disalignment of the respective edges 20 and 21 of the holes in the bracket. Such disengagement is readily obtained by raising the slide enough to bring the tongue 24 directly behind the perforation 30, then moving the slide rearwardly so that the tongue passes out through the perforation, after which the slide may again be moved vertically.

As shown by the dash-dot lines of Fig. 6, by bending the upper flange 14 of the bracket 12 at a more obtuse angle to the web 16, the edge 20 of the hole 18 is moved rearwardly and the angle of possible tilt of the slide accordingly increased, whereby the angle of tilt may be adjusted if desired.

For ease in manipulating the slide when it is desired to mount, remove or replace curtains, an inexpensive handle 32 is formed at the lower end of the slide by continuing the flanges 29 thereof past the lowermost end

edge 33 of the web 28 and bending the flanges to extend outwardly (Fig. 3). In order that a curtain rod 10 of any of the usual types, now largely conventional, may be secured to the upper ends of the pair of slides 13, each slide may be provided with a slot 34 in each of the flanges 29 thereof, the slots of one flange being aligned with the slot of the other flange to receive the back or web 35 of a conventional curtain rod bracket having outstanding flanges 37 each adapted to engage a curtain rod. A pair of suitable screws as 38 threaded into the web 28 press the back 35 against the rear walls of the slots 34 thereby to secure the brackets in place as shown in Fig. 3. To mount a bracket 40 having a single flange 41 designed to support a single curtain rod, the back 42 of the bracket 15 may be screwed directly to the front face of the web 28 of the slide as shown in Fig. 7. In either case, the curtain rod itself ties the upper ends of the slides together against relative movement and serves as the sole brace therefor and forms a reinforced structure therewith movable up and down as a unit.

As shown in Figs. 8 and 9, the curtain rod bracket 44 may be secured to the rear faces of the turned flanges 45 at the rear of the reduced upper ends of the flanges 29 of the slide 46 by bolts as 47. At least one of the bolts 25 passes through a slot as 48 in the web 28. This permits variation of the vertical distance between bolts to accommodate various brackets having different distances between the screw holes thereof, as for example, brackets for curtain rods designed to hold draw-pull curtains or the like.

If the respective slides of a pair of such slides be too far apart for convenient handling, as in the case of unusually wide windows, the user may drop one slide the distance between perforations by pushing the slide rearwardly enough to disengage it from the tongue 24 as previously described after first raising the slide slightly; after the slide so dropped is locked in its new position, the other slide is similarly disengaged, dropped a convenient distance and locked, the operation being repeated until 30 both slides are in the lowermost positions thereof and the curtain and its rod are easily accessible. If the curtain is heavy, it may be raised into place in a similar manner, one or more perforations at a time.

It will now be seen that I have provided a simple and inexpensive two-piece device for raising and lowering, 45 curtains; that each piece is adapted to be stamped with a minimum of labor from sheet metal or the like for quantity production; that the slide need be supported only at the lower end thereof; that the slide-supporting tongue also acts as a guide for the slide and cams the slide automatically rearwardly away from the tongue when the slide is raised; that the slides may be tilted so that the upper ends thereof engage the window frame if desired; that the slides are adapted to carry conventional curtain-rod brackets of any of the usual types; that the curtain rod 50 serves to brace the upper ends of the slides against undesirable displacement or movement and that I have provided a device well designed to meet the requirements of commercial use and sale.

While certain specific embodiments of the invention 55 have herein been shown and described, various obvious changes may be made therein without departing from the spirit of the invention defined in the appended claims.

I claim:

1. A two-piece curtain rod elevator comprising a normally raised upright slide having vertically spaced apart perforations therein, and relatively fixed combined guide and locking means normally maintaining the slide in the uppermost position thereof comprising a slide-engaging bracket having a pair of vertically spaced holes therein for the passage therethrough of the slide and an integral fixed rigid upwardly extending tongue at the front edge of one of the holes adapted to enter a selected perforation of the slide, the slide being movable downwardly in the 60 holes of the bracket until the tongue enters one of the

perforations, and one of the holes being elongated to a length greater than the width of the slide measured between the front and rear edges of the slide.

2. The combination of claim 1, the slide being slidable in said holes and being tiltable out of the vertical in said holes to clear a window sill in the lowermost position of the slide, said slide being locked at its lower portion in said position between the tongue and said front edge of the tongued hole.
